United States Patent Office

Des. 201,929
Patented Aug. 10, 1965

201,929

OVERHEAD PROJECTOR

Henry T. Wilton, Buffalo, and John T. Armbruster,
Niagara Falls, N. Y., assignors to American Optical
Company, Southbridge, Mass., a voluntary association
of Massachusetts

Filed Aug. 7, 1964, Ser. No. 81,195

Term of patent 14 years

(Cl. D61—1)

Fig. 1

Fig. 2

Fig. 3

FIG. 1

FIG. 2

FIG. 1 is a top plan view of an overhead projector showing our new design;

FIG. 2 is a left-side elevational view thereof;

FIG. 3 is a front elevational view thereof;

FIG. 4 is a right-side perspective view thereof; and

FIG. 5 is a rear perspective view thereof.

The essential features of our design reside in the portions shown in full lines in the drawings.

We claim:

The ornamental design for an overhead projector, as shown and described.
